SUCTION BAILER

Elmo L. Condra, Long Beach, Calif.

Application February 19, 1946, Serial No. 648,724

9 Claims. (Cl. 166—19)

1

This invention relates to a suction bailer to be used in wells for the purpose of removing sand and dirt and other accumulation in the well.

This invention relates to the type of bailer having a self contained plunger which is reciprocated by means of a supporting cable, this plunger on reciprocation creating a reduced pressure within the tool, thus drawing sand and other material or articles into the barrel of the tool so that this material can be lifted to the surface.

An object of my invention is to provide a novel suction bailer wherein an automatic valve opens when there is pressure in the tool, thereby relieving this pressure, but the valve remains closed as long as there is a reduced pressure or suction in the tool.

Another object is to provide a novel bottom valve assembly in a suction bailer whereby ports are automatically opened when the tool enters a layer of sand or other material, and the valve closes as soon as the tool is lifted.

A feature of my invention resides in the spring which tends to close the bottom sleeve valve and also acts as a centering means for the tool.

Still another feature is to provide a novel pressure relief valve within the tool, this valve being automatically opened as soon as a predetermined pressure has been built up within the tool.

Other objects, advantages and features of invention may appear from the accompanying drawing, the subjoined detailed description and the appended claims.

In the drawing:

Figure 1 is a quarter sectional view of the upper part of my bailer showing the reciprocating plunger.

Figure 2 is a quarter sectional view of the lower part of my bailer.

Figure 3 is a quarter sectional view of the valve portion of my bailer showing the valve in closed position.

Referring more particularly to the drawing, bailers are frequently used in casing or tubing, which is usually placed in a well such as an oil well. This tubing or casing is shown at 1, and is usual and well known in the art. My suction bailer 2 consists of an outer barrel 3, which is formed in a plurality of sections, which will be subsequently described in detail. A plunger 4 extends into the top of the barrel through a packing gland 5. A fitting 6 on the top of the plunger enables this plunger to be attached to a cable socket 7, in which the cable 8 is secured. The entire tool is suspended on the cable 8 and also, as this cable is reciprocated, the plunger 4 will

2

move due to the fact that the tool is resting on the sand or other material which is within the pipe or tubing 1.

On the lower part of the barrel 3, there is 5 mounted or attached a shoe 9, in which a plurality of side inlet ports 10 are cut. A nipple 11 screws into the lower end of the shoe 9, and a releasing valve 12 is mounted in the nipple 11 so that the fluid or other material in the bailer can 10 be removed when the tool is withdrawn from the well. This valve 12 is usual and well known in bailers of this type. A sleeve 13 is slidably mounted on the outside of the shoe 9 and normally covers the ports 10—that is, gravity will 15 normally hold the shoe in the lower position and also a spring 14 urges the sleeve downwardly. The spring 14 is barrel shaped so that it will engage the pipe or tubing 1, and thus tend to center the bailer. As the bailer is dropped into the sand or other material, the sleeve 13 will be forced 20 upwardly against the tension of the spring 14, thus opening the ports 10 so that sand and other material can enter the bailer.

It is obvious that as the plunger 4 is reciprocated a suction will occur on one stroke, and a pressure on the opposite stroke. To prevent the building up of pressure within the tool, I provide 25 an automatic valve, which automatically opens when a predetermined pressure occurs within the bailer, and this valve consists of the following:

A tubular valve 15 is guided in the pipe coupling 30 16. An annular packing 17 is provided in the top of the valve 15, and this packing engages the ring 18 in the closed position of the valve. The ring 18 is mounted in the pipe coupling 19 in a suitable manner such as welding, brazing, etc. A plurality of ports 20 are cut in the wall of the bailer, and as the valve 15 moves downwardly, these ports are opened, thus permitting the 35 escape of any pressure in the barrel. A ring 21 bears against the bottom of the tubular valve 15, and a spring 22 bears against the ring and urges the tubular valve upwardly to its closed position. Fabric boots 23 and 24 are attached 40 to the top and bottom of the tubular valve 15 respectively, and act to prevent the accumulation of any material such as sand on the outside of the valve which might prevent its free sliding movement. The spring 22 rests on a nipple 25, 45 and this nipple threads into a coupling 26. The tension of the spring 22 can be adjusted by threading the nipple 25 in or out of the coupling 26.

In operation, the tool is lowered into the well 50 and sinks into the sand or other material in the

well due to its weight. As the tool sinks into the sand, the sleeve 13 is pushed upwardly against the tension of the spring 14. The ports 10 are now open, and the sand or the like, can enter the tool. The cable 8 is now reciprocated, which moves the plunger 4 and each upstroke of the plunger will create a reduced pressure within the bailer. This suction within the bailer causes the sand or other material to be forced through the ports 10, and will fill the lower part of the bailer. The down stroke of the plunger 4 will tend to create a pressure in the bailer, and as pressure is built up, it will act on the upper surface of the tubular valve 15, pressing this valve downwardly against the tension of the spring 22. Since there is a larger area on the top of the valve than on the bottom, the valve will be forced downwardly off of its seat. The ports 20 will thus be opened and the pressure will be relieved. As soon as this pressure relief occurs, the spring 23 again closes the valve 15, and the plunger 4 continues to partially evacuate the bailer on its next upstroke. Any pressure without the bailer will act on the top surface of the ring 21, as well as against the bottom surface of this ring, and consequently, this ring is placed as far as pressure is concerned. Consequently, the only upward thrust tending to close the valve 15 is the spring 22.

Having described my invention, I claim:

1. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the said tubular valve, said tubular valve being movable to open said ports when a predetermined fluid pressure in the bailer is exerted on said valve, a shoulder on said valve against which the fluid pressure is exerted to open said valve, and spring means engaging the tubular valve and urging said valve into position to close said ports, and a valve seat on the interior of the outer barrel in the upper end of said tubular valve, engageable by said valve when in port closing position.

2. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the said tubular valve, said tubular valve being movable to open said ports when a predetermined fluid pressure in the bailer is exerted on said valve, a shoulder on said valve against which the fluid pressure is exerted to open said valve, and spring means engaging the tubular valve and urging said valve into position to close said ports, and flexible boots mounted on both the upper and lower ends of the tubular valve, said boots closing the space between the outside of the valve and the inside of the barrel to prevent accumulation of sand on the outside of said valve.

3. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the said tubular valve, said tubular valve being movable to open said ports when a predetermined fluid pressure in the bailer is exerted on

said valve, a shoulder on said valve against which the fluid pressure is exerted to open said valve, and spring means engaging the tubular valve and urging said valve into position to close said ports, and a valve seat on the interior of the outer barrel at the upper end of said tubular valve engageable by said valve when in port closing position, and flexible boots mounted on both the upper and lower ends of the tubular valve, said boots closing the space between the outside of the valve and the inside of the barrel to prevent accumulation of sand on the outside of said valve.

4. In a suction bailer comprising an outer barrel, a plunger slidably extending into the barrel, a cable attached to the plunger whereby said plunger is reciprocated, a tubular valve, mounted for vertical movement in the barrel below the plunger, said barrel having exhaust ports therein adjacent the said tubular valve, said tubular valve being movable to open said ports when a predetermined fluid pressure in the bailer is exerted on said valve, a shoulder on said valve against which the fluid pressure is exerted to open said valve, and spring means engaging the tubular valve and urging said valve into position to close said ports, a shoe on the lower end of said barrel, said shoe having ports in the side thereof, a sleeve slidably mounted on the shoe and movable to open said ports in said shoe in one position of the sleeve, and a spring engaging the sleeve and urging said sleeve into position to close said ports in said shoe.

5. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the said tubular valve, said tubular valve being movable to open said ports when a predetermined fluid pressure in the bailer is exerted on said valve, a shoulder on said valve against which the fluid pressure is exerted to open said valve, and spring means engaging the tubular valve and urging said valve into position to close said ports, and a valve seat on the interior of the outer barrel at the upper end of said tubular valve engageable by said valve when in port closing position, a shoe on the lower end of said barrel, said shoe having ports in the side thereof, a sleeve slidably mounted on the shoe and movable to open said ports in said shoe in one position of the sleeve, and a spring engaging the sleeve and urging said sleeve into position to close said ports in said shoe.

6. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the said tubular valve, said tubular valve being movable to open said ports when a predetermined fluid pressure in the bailer is exerted on said valve, a shoulder on said valve against which the fluid pressure is exerted to open said valve, and spring means engaging the tubular valve and urging said valve into position to close said ports, and flexible boots mounted on both the upper and lower ends of the tubular valve, said boots closing the space between the outside of the valve and the inside of the barrel to prevent accumulation of sand on the outside of said valve, a shoe on the lower end of said barrel, said shoe having ports in the side thereof,

a sleeve slidably mounted on the shoe and movable to open said ports in said shoe in one position of the sleeve, and a spring engaging the sleeve and urging said sleeve into position to close said ports in said shoe.

7. In a suction bailer including an outer barrel, a plunger slidably extending into the barrel, a cable attached to the plunger whereby said plunger is reciprocated, a shoe on the lower end of the barrel, said shoe having ports in the side thereof, a sleeve slidably mounted on the shoe and adapted to close said ports in one position of the sleeve, a tubular relief valve mounted for vertical movement, in the barrel and positioned below the plunger, said barrel having ports in the side thereof, adjacent the tubular relief valve, said ports being opened on movement of the tubular valve when a predetermined fluid pressure in the bailer is exerted on said tubular valve, a shoulder on said valve against which the pressure is exerted to open said valve, an annular seat on the interior of the outer barrel at the upper end of the valve engageable by said valve when in port closing position, and a spring bearing against the lower end of the valve whereby said valve is urged into closed position.

8. In a suction bailer including an outer barrel, a plunger slidably extending into the barrel, a cable attached to the plunger whereby said plunger is reciprocated, a shoe on the lower end of the barrel, said shoe having ports in the side thereof, a sleeve slidably mounted on the shoe and adapted to close said ports in one position of the sleeve, a tubular relief valve mounted for vertical movement, in the barrel and positioned below the plunger, said barrel having ports in the side thereof, adjacent the tubular relief valve, said ports being opened on movement of the tubular valve, when a predetermined fluid pressure in the bailer is exerted on said tubular valve, a

shoulder on said valve against which the pressure is exerted to open said valve, an annular seat on the interior of the outer barrel at the upper end of the valve engageable by said valve when in port closing position and a spring bearing against the lower end of the valve whereby said valve is urged into closed position, and flexible boots on the upper and lower ends of the valve, said boots extending between the valve and the inside of the barrel whereby accumulation of sand around the valve is prevented.

9. In a suction bailer comprising an outer barrel, a plunger slidably extending into the barrel, a cable attached to the plunger whereby said plunger is reciprocated, a tubular valve mounted for vertical movement in the barrel below the plunger, said barrel having exhaust ports therein adjacent the tubular valve, said valve being movable to open said ports when a predetermined fluid pressure in the bailer is exerted on said valve, a shoulder on said valve against which the fluid pressure is exerted to open the valve, spring means engaging the tubular valve and urging said valve into position to close said ports, a ring seat on the interior of the outer barrel at the upper end of said tubular valve, engageable by said valve when in port closing position.
